UNITED STATES PATENT OFFICE.

JOHN W. EISENHUTH, OF DETROIT, MICHIGAN.

INTERNAL-COMBUSTION ENGINE.

1,233,563.

Specification of Letters Patent. Patented July 17, 1917.

Application filed June 10, 1912. Serial No. 702,783.

To all whom it may concern:

Be it known that I, JOHN W. EISENHUTH, a citizen of the United States, residing at Detroit, in the county of Wayne and State 5 of Michigan, have invented certain new and useful Improvements in Internal-Combustion Engines, of which the following is a specification, reference being had therein to the accompanying drawing.

10 This invention relates to internal combustion engines and has special reference to a compound internal combustion engine wherein after the explosion in one cylinder, the same being the high pressure cylinder, 15 the gases will be conducted to a low pressure cylinder.

One object of the invention is to improve and simplify the general construction of devices of this character.

20 A second object of the invention is to provide an improved gas engine wherein a plurality of four-cycle high pressure engines will operate to exhaust alternately into a two-cycle low pressure engine.

25 A third object of the invention is to provide an improved form of valve especially adapted for use in connection with such engines.

A fourth object of the invention is to provide an improved means for scavenging a 30 high pressure engine after the explosion of the gases has taken place.

A fifth object of the invention is to provide an improved form of valve arrangement for multi-cylinder internal combustion engines.

A sixth object of the invention is to provide an improved low pressure cylinder arrangement wherein the lower end of the low 40 pressure cylinder will act as a four-cycle single acting internal combustion engine.

A seventh object of the invention is to provide an improved method for operating multi-stage internal combustion engines.

45 With the above and other objects in view the invention consists in general in certain novel cylinder, valve and other arrangements of parts and combinations of details hereinafter fully described, illustrated in 50 the accompanying drawings, and specifically claimed.

In the accompanying drawings like characters of reference indicate like parts in the several views, and:

Figure 1 is a side elevation of the engine 55 taken from the cylinder side.

Fig. 2 is a side elevation of the engine taken from the valve side.

Fig. 3 is a plan view of the engine partly in section on the line 3—3, Fig. 2, certain of 60 the pistons being omitted more clearly to show the passages.

Fig. 4 is a section taken on the line 4—4, Fig. 2.

Fig. 5 is a section taken on the line 5—5, 65 Fig. 2.

Fig. 6 is a vertical median section taken longitudinally of the engine, the positions of the pistons being indicated by dotted shading.

Fig. 7 is a partial detail section taken vertically through the valve chest.

Figs. 8, 9, 10, and 11 are diagrammatic views showing the relative conditions prevailing in the upper valve chests at the same 75 time.

Fig. 12 is a diagrammatic view illustrating the relative rotations of the various valves.

Fig. 13 is a detail showing the engine applied to an automobile.

Fig. 14 is a detail view of one of the low pressure pistons showing the skirt hereinafter referred to.

This engine is provided with the usual 85 base 20 whereon is mounted the frame 21. Suitably arranged within the casing formed by the base and frame are certain bearings 22 wherein is journaled a shaft 23 provided with a plurality of cranks 24.

90 In the present embodiment six cylinders are employed which are arranged in two groups of three each, there being a low pressure cylinder located between a pair of high pressure cylinders in each group, the 95 center lines of the cylinders all lying in the same plane. The center crank of each group is arranged at an angle of 180° to the remaining cranks and the cranks of one group are quartered with respect to the cranks of 100 the other group. These cylinders are preferably cast integral with the frame, all ports

and like parts, together with the water jacketing being cored in one casting so as to produce a unit structure.

In carrying out the above arrangement 5 the low pressure cylinder is indicated at 25 and this cylinder has a reduced extension 26 running below the lower end of the cylinder and projecting slightly up therein as indicated at 27. At each side of this low 10 pressure cylinder there is provided a high pressure cylinder 28 of the ordinary form. Each of the low pressure cylinders has a piston 29 which has a reduced extension 30 fitted closely in the extension 26 of the low 15 pressure cylinder, and suitable packing, not deemed necessary here to be shown as the same, is of the ordinary type, is used to insure a gas-proof joint between the extensions. The piston itself is also provided 20 with the usual rings or other like means of rendering the joint gas tight.

In each of the high pressure cylinders there is provided a piston 31. These various pistons are connected to the cranks 24 by 25 piston rods 32 of any preferred type.

By reason of the reduced extension 30 on the low pressure piston an annular passage or chamber 33 is formed around this extension and it will be plain that if a charge of 30 gas be exploded compressed in this annular passage the reduced effective area of the piston will constitute a third high pressure piston in each group.

Arranged along the side of the engine and 35 cast integral therewith is a series of water-jacketed valve chests 34, there being four chests arranged side by side and two in vertical alinement below the center chests of the four as can readily be seen by reference 40 to Fig. 2. Connecting the two upper chests of each set is a passage 35 which opens by means of intake ports 36 into the respective chests. At the end of the passage 35 adjacent the center of the engine there is provided a passage 37 which runs down to the 45 lower chest 34 of the respective set and opens into said chest through a port 38. Centrally disposed of each of the passages 35 is a flange 39 whereto may be connected 50 the intake manifold pipe leading from the carburetor or such other source of carbureted air as may be employed.

These ports 36 and 38 are preferably in the upper part of the respective chests 55 and extend longitudinally thereof. Spaced around the respective chests from these ports are other ports 40 which communicate with passages 41 leading to the respective inlet ports 42 of the low pressure cylinder, these 60 being located adjacent the top of that cylinder.

From the lower end of each valve chest a passage 43 extends to each high pressure cylinder, the passage opening into the re-

spective high pressure cylinder and valve 65 chest by means of similar ports.

Within each of the valve chests is a rotary valve and this valve consists of a pair of cylindrical cup-shaped members, there being a major member 44 located in the upper end of the valve chest and a minor member 45 located in the lower end thereof. These cup-shaped structures face each other and are connected by any suitable means, as by the bar 46 which holds them with their 70 edges in spaced relation. One of these members terminates above the passage 43 of the respective chest while the other has its upper edge lying below so that the passage 43 is in constant communication at all times 75 with the high pressure cylinder.

In the major member 44 is formed a port opening 47 which is so arranged as to successively communicate with the ports 40 and 36 as the valve rotates. In order to rotate 80 these valves they are provided with stems 48 which pass through the casings or chests and extend downward therefrom. On each of these stems there is provided a beveled gear 49 which meshes with a beveled gear 90 50 carried on a shaft 51 which is actuated by suitable gearing, as indicated in general at 52, from the main shaft 23. It is to be observed that as the shafts are symmetrically arranged with respect to their port 95 openings in each group the valves of each group will revolve in opposite directions. All of these gears are preferably incased in as indicated at 53 to prevent injury from dust and dirt.

At the lower end of each of the low pressure cylinders there is provided a port 54 and the passage 43 leading from each of the lower casings 42 communicates with this port, thus opening beneath the piston 29. 105 On each of the pistons 29 there is a downwardly projecting skirt 55, shown in Fig. 14, which, when the piston is in its lowermost position, will close the respective port 54 irrespective of the position or movement 110 of any valve, the skirt being received in the annular passage 33 between the inward extension 27 and the outer wall of the low pressure cylinder.

Secured to one side of the frame 21 is a 115 vacuum chamber 56 which communicates with ports 57 located intermediate the ends of the respective low pressure cylinders, the ports being uncovered when the low pressure piston is at its lowermost point. Leading from this vacuum chamber to a vacuum pump 58 is a pipe 59. This pump may be driven by any suitable means as by a separate motor, or by shafting run from the main or valve shaft of the present engine as 120 125 may be found desirable.

Opposite this vacuum chamber 56 is an exhaust passage 60 which communicates with

the vacuum chamber by means of a cross-over 61 and with the open air through a suitable opening normally held closed by a shifting valve 62 so that in case of any back-firing the exhaust chamber may be relieved therefrom.

It is to be noted that the port 47 in each major valve member is of such length that at one period of its revolution it overlaps to 10 a predetermined extent the adjacent edges of ports 40 and 36 so as to leave a clear passage from one port to another.

By this means there is provided a novel method of scavenging the engine for when 15 these ports are thus momentarily opened to each other the powerful vacuum maintained will instantly draw a charge of fresh carbureted air through the valve and thus clear the valve of any burnt gases that may re- 20 main therein the same having not been forced out by the upward stroke of the high pressure piston.

All of the parts of this engine with the exception of the vacuum chamber are provided with the usual water jacket 63.

In the operation of the engine let it be supposed that the parts are in the position shown in Fig. 6 and that the left hand piston is the next to be fired, the other cylinders being free from gas. Now, upon the cranking of the engine the charge of carbureted air will be drawn into the left hand high pressure cylinder. Upon the completion of one revolution this charge will then 35 compress. Thereupon the charge is ignited in any preferred manner and the piston driven downward. As this piston passes downward the valve of the right-hand cylinder of that group will then open to the carburetor so that its piston will also draw in a charge of carbureted air when coming down. At this time the valve of the left hand cylinder has turned to such a position as to place the valve in communication with 45 the upper part of the low pressure cylinder whose piston at the moment will be at the upper end of the stroke. Thereupon the charge from the left hand cylinder expanding will force the low pressure piston downward until the ports 57 are uncovered. 50 When this takes place the burnt gases rush violently into the vacuum chamber, the vacuum being constantly maintained by running the pump 58.

Now the explosion takes place in the right hand cylinder of that group. The low pressure piston ascends and the two high pressure pistons descend, the left hand one drawing in a fresh charge. When the right 60 hand high pressure piston reaches the bottom of the stroke its valve again places the low pressure cylinder in communication with the right hand valve chest whereupon the gases from the right hand cylinder force

the low pressure piston downward while, at 65 the same time, the high pressure pistons move upward.

It is to be observed from this that the gases are exploded on every complete revolution in one of the two high pressure cylinders so that the low pressure piston receives an impulse from the exploded gases on every revolution, thereby causing the low pressure engine to act as a two-cycle engine while the high pressure engines are 75 each four-cycle engines.

The operation just referred to takes place at one end of the engine while a similar operation is taking place at the opposite end of the engine with the exception that 80 the operation there is advanced one-half stroke in each cylinder over that in the similar cylinder in the first mentioned end.

By this means a single two-cycle engine is operated in combination with a plurality 85 of four cycle engines, the same forming a compound engine.

In describing the above operation the lower end of the low pressure cylinder which constitutes the third four-cycle high 90 pressure engine has not been referred to, but this lower end operates in unison with either one, preferably the one toward the center of the high pressure engines. Under normal conditions this lower end is opened to the 95 atmosphere by means of a suitable valve, but in hill climbing and the like where it is desired to have the fullest possible power the three high pressure engines in each group are used by closing the valve whereupon the 100 low pressure cylinder receives alternate impulses from one of the high pressure explosions and from two high pressure explosions simultaneously.

Having thus described the invention, what 105 is claimed is:—

1. A compound internal combustion unit comprising a set of high pressure cylinders and an intermediate low pressure cylinder, pistons for each cylinder, divergent radial 110 ports at one side of the low pressure cylinder, and valve chambers therefor disposed between the low pressure and the high pressure cylinders, ports connecting the said chambers to respective high pressure cylinders, a pair of relatively symmetrically 115 arranged valves disposed in said chambers and operative to alternately connect the high pressure cylinders to the lower through said ports, and a lateral intake chamber for fuel 120 having symmetrical openings to said valve chambers, and formed integrally therewith.

2. A compound internal combustion unit comprising a set of high pressure cylinders and an intermediate low pressure cylinder, pistons for each cylinder, divergent radial 125 ports at one side of the low pressure cylinder, and valve chambers therefor disposed

between the low pressure and the high pressure cylinders, ports connecting the said chambers to respective high pressure cylinders, a pair of relatively symmetrically arranged valves disposed in said chambers and operative to alternately connect the high pressure cylinders to the lower through said ports, a lateral intake chamber for fuel having symmetrical openings to said valve chambers, and an exhaust and vacuum chamber communicating with said low pressure chamber, and momentarily through an open valve to the intake chamber whereby the respective connected passages are scavenged.

3. A compound, internal combustion engine comprising a shaft, a casing having two sets of interacting high and low pressure cylinders all arranged in a plane of said shaft, pistons therein connected to the shaft, the low pressure cylinders of each set being disposed between its respective high pressure cylinders, a set of valves for the high pressure cylinders arranged in pairs with symmetrical ports, means for operating said valves simultaneously, and a common exhaust chamber disposed centrally of the casing and at one side of the adjacent central high pressure cylinders and connecting with the low pressure chambers, the valves controlling flow from the high pressure cylinders to respective low pressure cylinders.

4. A compound, internal combustion engine having a high pressure cylinder and a

low pressure cylinder, a valve chamber having a port at one end leading to the high pressure cylinder and a pair of ports at its opposite end, one leading to an intake chamber and one to the low pressure cylinder, and a valve controlling flow from the intake to the high pressure cylinder and also from the latter to the low pressure cylinder.

5. A compound, internal combustion engine having a high pressure cylinder and a low pressure cylinder, a valve chamber having a port at one end leading to the high pressure cylinder and a pair of ports at its opposite end, one leading to an intake chamber and one to the low pressure cylinder, and a valve controlling flow from the intake to the high pressure cylinder and also from the latter to the low pressure cylinder, a piston in the low pressure cylinder having a differential diameter and fitting at its smaller end a reduced portion of said low pressure cylinder to form a high pressure piston on one side, a second valve chamber alining with the first and having ports in its wall, and a second valve axially alining with the first, and controlling flow through the second chamber.

In testimony whereof I hereunto affix my signature in presence of two witnesses.

JOHN W. EISENHUTH.
